CLAIM

An ornamental design for a washbasin, as shown and described.

DESCRIPTION

FIG. 1 is a perspective view of my washbasin taken from the top front and left side;

FIG. 2 is a plan view of the top side thereof;

FIG. 3 is a plan view of the left side thereof, the right side being the mirror image of the left side;

FIG. 4 is a plan view of the front side of the washbasin of FIG. 1;

FIG. 5 is a plan view of the rear side thereof;

FIG. 6 is a plan view of the underside thereof; and,

FIG. 7 is a perspective view of an alternative embodiment of my washbasin taken from the top front and left side, wherein the basin is a light-transmitting material.
